CLAIM

The ornamental design for a shoe sole, as shown and described.

DESCRIPTION

FIG. 1 is a bottom perspective view of a shoe sole showing my design;

FIG. 2 is a front elevational view of the shoe sole of FIG. 1; FIG. 3 is a back elevational view of the shoe sole of FIG. 1; FIG. 4 is a right side elevational view of the shoe sole of FIG. 1;

FIG. 5 is a left side elevational view of the shoe sole of FIG. 1;

FIG. 6 is a top plan view of the shoe sole of FIG. 1; and, FIG. 7 is a bottom plan view of the shoe sole of FIG. 1. The broken lines shown on the shoe upper in FIGS. 1-7 are for illustrative purposes only and form no part of the claimed design.

1 Claim, 6 Drawing Sheets(56)
